UNITED STATES PATENT OFFICE.

MAHLON H. FINE, OF ALDEN STATION, PENNSYLVANIA.

LUBRICATOR.

SPECIFICATION forming part of Letters Patent No. 482,846, dated September 13, 1892.

Application filed January 21, 1892. Serial No. 418,771. (No model.)

To all whom it may concern:

Be it known that I, MAHLON H. FINE, a citizen of the United States, residing at Alden Station, in the county of Luzerne and State 5 of Pennsylvania, have invented a new and useful Lubricator, of which the following is a specification.

This invention relates to oil-cups; and it has for its object to provide an oil-cup or revolving lubricator that is designed to be secured to the sleeve or drum of any friction-gearing and which will deposit the lubricant upon the shaft over which the sleeve or drum revolves at every revolution of said sleeve 15 and which will only feed at such intervals when in motion and while stationary will not feed. It is thus the primary object of this invention to provide an oil-cup which materially saves oil and prevents the friction devices 20 from becoming greasy and out of order, while at the same time sufficient lubricant is fed to the shaft to prevent the sleeve from cutting.

With these and many other objects in view, which will readily appear as the nature of the 25 invention is better understood, the same consists in the novel construction, combination, and arrangement of parts hereinafter more fully described, illustrated, and claimed.

In the accompanying drawings, Figure 1 is 30 a front elevation of a friction-controlled sleeve or drum provided with oil-cups constructed and arranged in accordance with my invention. Fig. 2 is a transverse sectional view through one of the oil-cups and the sleeve 35 with which the same is connected. Fig. 3 is a detail in plan of the buffer or cushion-cap. Fig. 4 is a detail in perspective of the buffer-plate.

Referring to the accompanying drawings, 40 A represents a shaft which accommodates the long sleeve or drum B, working over said shaft, which is supported in suitable bearings at each end, according to its location. Keyed upon each end of the revolving sleeve 45 or drum B are the spiders or wheels C, which are adapted to control the movement of said sleeve or drum. This gearing is a portion of the friction-gearing used for hoisting purposes, and is sufficient to show the adaptation of my improved oil-cups thereto. Motion is imparted to the shaft A by suitable 50 gearing and by means of suitable friction

clutches or devices thrown into engagement with the said spiders. The said drum or sleeve B may be thus revolved with the shaft 55 to hoist, while, on the other hand, when the friction devices are thrown out of contact with said spiders the said drum will revolve loosely upon the shaft and lower the object hoisted. This will be quite apparent. The 60 said sleeve or drum B is provided with the upwardly-extending threaded nipples D, which receive the threaded lower end of the spout E of the funnel-shaped oil-cup or revolving lubricator F. The bore of the spout 65 E is slightly greater than the bore of the nipples opening onto the axle, the purpose of which being readily apparent. The said oil-cup F is provided with an upper exteriorly-threaded neck G, which receives the detachable cover H, engaging said neck and provided upon the under face with a clamping-plate I, having a series of clamping-arms J, that are adapted to receive and removably clamp in position the rubber cushion or buffer K. A feeding-plunger L works within 70 said funnel-shaped oil-cup and through the spout E thereof and into the nipples in the revolving sleeve or drum, and as the said sleeve revolves and carries the oil-cups therewith it can be readily seen that the said feeding-plunger will alternately be thrown back against the cushion upon the inclosing cap to allow the oil to flow from the spout into the nipples and into said nipples D in the sleeve 75 or drum to carry the portion of the lubricant worked therein to the shaft against which the plunger will strike. A continuous lubrication of the shaft and sleeve is thus obtained as long as the said sleeve is in motion; 80 but the lubrication ceases when the revolutions of the sleeve cease. It is not designed to fill the oil-cup with running oil, but with a lubricating-grease which will not freely run whenever the oil-cup may be in a vertical position but portions of which can only be carried to the shaft by the working feeding-plunger. The cushion not only prevents a wearing upon the inclosing cap and cushions the shock of the feeding-plunger thereon, but also serves as a spring to assist in 85 throwing the plunger into the spout and nipple, and said cushion may be easily and readily replaced when damaged or worn out, as 90 95 100

will be readily seen. It may be further observed at this point that the plunger L fits or works within the spout E only sufficiently tight so as to guide the same, in order that the lubricant may work into the reduced nipple when the plunger has been thrown back against the cushion, and, on the other hand, when the lubricator has assumed a vertical position to allow the plunger to be thrown into the nipple the said plunger fits the nipple tightly, so as to form a valve which prevents the oil working down into the nipple without the use of valves.

The construction, adaptation, and uses of the herein-described oil-cup are thought to be apparent without further description.

It may be additionally noted that this revolving lubricator is also especially adapted to be used at the head of slopes or shafts of mines particularly or in any location on machinery where it is necessary to use a sliding sheave for hoisting purposes. By drilling a hole through the hub of the sheave the lubricator is readily attached, and thus insures a perfect lubrication of the shafting and also of the sheave. At the same time the revolving lubricator materially saves the oil, as already stated, inasmuch as the same does not feed unless the sheave, sleeve, or other portion of machinery to which it is attached is in motion. Much oil is lost by the ordinary

lubricating devices used in connection with sliding sheaves by throwing the loose oil on the shafting, which in every case is scraped off the first time the sheave slides across the shaft.

Having thus described my invention, what I claim, and desire to secure by Letters Patent, is—

The combination, with a shaft and a sleeve or drum working thereover and having a threaded nipple, of a funnel-shaped oil-cup or revolving lubricator carried by said sleeve or drum and provided with a threaded spout secured within said nipple and of a less diameter than the same and an inclosing cap or cover provided with a clamping-plate having a series of clamping-jaws, a buffer and spring-imparting cushion removably secured between said clamping-jaws, and a feeding plunger-rod, of the same diameter throughout, working in said oil-cup and spout and adapted by the revolutions of said sleeve to be thrown alternately against said cushion and the shaft, substantially as set forth.

In testimony that I claim the foregoing as my own I have hereto affixed my signature in the presence of two witnesses.

MAHLON H. FINE.
